UNITED STATES PATENT OFFICE.

SHELBY PATRICK, OF DURANGO, COLORADO.

ARTICLE-HOLDING RACK.

1,221,584.

Specification of Letters Patent.

Patented Apr. 3, 1917.

Application filed April 3, 1916. Serial No. 88,561.

To all whom it may concern:

Be it known that I, SHELBY PATRICK, a citizen of the United States, residing at Durango, in the county of La Plata and State of Colorado, have invented certain new and useful Improvements in Article-Holding Racks; and I do declare the following to be a full, clear, and exact description of the invention, such as will enable others skilled in the art to which it appertains to make and use the same.

This invention relates to improvements in racks for holding and locking gymnasium apparatus, tools, and similar articles.

The main object of the invention is to provide a device of this character which will effectively hold numerous articles of the classes enumerated and prevent their being stolen or otherwise misplaced.

With this general object in view, my invention consists in certain novel features of construction, and the combination and arrangement of parts which will hereinafter be more particularly described and claimed and shown in the drawings wherein:

Figure 1 is a plan view of my article holding rack, the parts being in unlocked position;

Fig. 2 is a similar view showing the parts in locked position;

Fig. 3 is a front elevation of the parts disposed as in Fig. 2;

Fig. 4 is a longitudinal section taken on the line 4—4 of Fig. 1;

Fig. 5 is a similar view taken on the line 5—5 of Fig. 2;

Fig. 6 is a transverse section taken on the line 6—6 of Fig. 1;

Fig. 7 is a detail perspective view of a portion of the upper plate;

Fig. 8 is a similar view of a portion of the lower plate; and,

Fig. 9 is still another perspective view of the locking lever removed.

In the embodiment illustrated, I have shown my invention as comprising a pair of elongated plates made of any suitable material, one stationary and the other slideable with respect thereto, the stationary plate being designated by the numeral 1 and the movable plate by the numeral 2. The stationary plate is preferably secured by one edge to the wall or other support of the gymnasium or the plate where it is to be used by any preferred means, thus pro-

jecting the same outwardly at right angles to the support. The lower movable member is secured to the upper by means of the bolts 3 which extend through apertures 4 in the stationary plate and through the elongated openings 5 in the slideable plate, nuts 6 being screwed on the ends of the bolts as shown. This arrangement allows a considerable range of movement on the part of the lower member, while at the same time secures it to the upper. The plates are also secured together by means of the U-shaped members 22, whose horizontal portions underlie the movable plate, while its arms extend up the front and rear edges thereof and are secured to the stationary plate 1. As many of these members may be employed as are necessary.

Any suitable means may be used for shifting this movable member but I preferably employ a bell-crank lever 7 for this purpose, said lever being pivoted as shown at 8 to the upright flange 9 of an angle member 10 which is secured by its horizontal flange 11 to the top of the stationary member. The short arm 12 of the lever 7 extends downwardly and has a longitudinal slot near its end as shown at 13 to receive a pivot bolt 14 which extends transversely through the movable member 2. The long arm 15 of the lever 7 is extended substantially parallel to the plates 1 and 2 when the same are in their locked positions, the free end of this arm 15 being provided with an opening 16 to receive a pad lock or other form of locking device P. This opening 16, when the arm 15 is in this horizontal position, aligns with an additional opening in the upright flange of a locking plate 17 preferably secured to the stationary member 1, the lock P extending through both of these openings. From this description, it will be seen that upon upward movement of the long arm of the bell crank lever 7, the movable member 2 will be shifted toward the left, and that when said arm is moved downwardly, into its substantially horizontal position, the movable member will be shifted in the opposite direction.

In order to utilize the structure just described for holding and locking gymnasium apparatus, tools and other articles having a reduced position interposed between their enlarged portions, I provide the upper stationary member with a longitudinal row

of pockets 18 preferably circular in shape and disposed vertically through the plate. The entrances to these pockets are formed by cutting flared openings 19 from the outer edge of the plate to the outer sides of said pockets, said openings being flared outwardly to facilitate the entrance of the articles thereinto. As shown in Figs. 1 and 2, the entrances to these pockets are disposed 10 at the opposite edge of the plate from the bell crank lever 7. The movable or lower member 2 is also provided with a longitudinal row of pockets 20 directly beneath the row in the upper plate, but these pockets 15 20 are elongated, the width, however, being substantially the same as the diameter of the first mentioned pockets 18 and alined therewith at all times. This plate has further, similarly flared entrance openings 21, said 20 openings being disposed at the ends of the elongated pockets.

When the bell crank lever 7 is in its raised position, the entrance openings 19 and 21 are alined so that the article to be disposed in the pockets, here shown to be a dumb bell D, can be readily inserted therein. As soon as the reduced portion of the dumb bell enters the pockets 18 and 20, the lever 7 can be lowered thus throwing the entrance openings out of alinement and preventing the removal of the dumb bell until the lower plate 2 is again shifted toward the left. By locking the end of the arm 15 of the bell crank lever to the locking plate 17, it will be seen 30 that the movable plate cannot be shifted so as to throw the openings 19 and 20 into alinement to release the dumb bell. It is obvious that the plates 1 and 2 can be made as long or short as desired and contain any 35 number of pockets, thus allowing a considerable number or only a few articles to be locked therein. While a dumb bell is herein shown for the sake of convenience, it is obvious that Indian clubs, or other forms 40

of gymnasium apparatus, tools, rifles, etc., 45 may be held by this improved rack.

I claim as my invention:

1. In a device of the class described, a stationary member, a slidable member coacting therewith, both having a plurality of 50 pockets, said pockets having openings extended through the edges of said members to form entrances thereto, said members being slidable to move the openings in the pockets into and out of alinement to unlock, 55 or lock the articles held in said pockets, an angle member secured to said stationary member, a bell crank lever pivoted thereto, one arm thereof being connected to the movable member to shift the same, a locking 60 plate on said stationary member, and means for securing the free end of said lever to said locking plate, whereby to hold the members in locked position.

2. In a device of the class described, a 65 stationary member, a slidable member coacting therewith, each having a plurality of pockets, said pockets having openings extended through the edges of the members to form entrances thereto, a U-shaped member 70 secured by its arms to the stationary member and surrounding the slidable member, a bolt carried by the stationary member, the slidable member having an elongated socket to receive said bolt, and means for moving 75 the slidable member to dispose the openings into the pockets into and out of alinement with each other to lock or unlock articles held in said pockets, said bolt being engaged by the ends of said socket to limit the movement of the slidable member. 80

In testimony whereof I have hereunto set my hand in presence of two subscribing witnesses.

SHELBY PATRICK.
